CLAIM

We claim the ornamental design for an oval fountain, as shown and described.

DESCRIPTION

FIG. 1 is a perspective view of an oval fountain embodying our invention;

FIG. 2 is a top plan view thereof;

FIG. 3 is a left side elevation view thereof;

FIG. 4 is a front elevation view thereof;

FIG. 5 is a bottom plan view thereof; and,

FIG. 6 is a rear elevation view thereof.

The portions of the design shown in broken lines are for illustrative purposes only and form no part of the claimed design.
